UNITED STATES PATENT OFFICE.

NORTON P. OTIS AND AUGUST SUNDH, OF YONKERS, NEW YORK, ASSIGNEES TO OTIS ELEVATOR COMPANY, OF EAST ORANGE, NEW JERSEY, A CORPORATION OF NEW JERSEY.

DOOR-LOCK.

SPECIFICATION forming part of Letters Patent No. 783,731, dated February 28, 1905.

Application filed September 14, 1903. Serial No. 173,112.

To all whom it may concern:

Be it known that we, NORTON P. OTIS and AUGUST SUNDH, citizens of the United States, residing at Yonkers, in the county of Westchester and State of New York, have invented certain new and useful Improvements in Door-Locks, of which the following is a specification.

Our invention relates to door-locks, and particularly to that class of door-locks which are used on doors for closing the entrance to an elevator well or hatchway at each landing.

We will describe a door-lock embodying our invention and then point out the novel features thereof in claims.

In the accompanying drawings, Figure 1 is a view, partly in elevation and partly in vertical section, of a portion of a door provided with a lock embodying our invention and showing the application of our invention at a landing for an elevator-car. Fig. 2 is a view in elevation of the door-lock shown in Fig. 1 with the parts in a position different from that shown in Fig. 1. A plate forming part of the casing of the lock is removed, as in Fig. 1, to show the interior of the lock.

Similar letters of reference designate corresponding parts in both of the figures.

A designates a portion of a door, and B a lock for the door. The lock B comprises a suitable casing b, a bolt or latch b', which slides into and out of its keeper on guides b'', and a tumbler b''. The bolt or latch is moved into and out of its keeper by means of an arm b'', carried by a spindle-sleeve b''. The tumbler b'' is movable into and out of position behind the bolt or latch b''. It is moved into position behind the bolt or latch b'' by means of an arm b'', and when in position behind the bolt or latch b'' the bolt or latch cannot be moved out of its keeper by the door-spindle. As here shown, the tumbler tends to move from behind the bolt or latch by gravity, and this movement by gravity takes place when the end of the arm b'' adjacent the tumbler falls to the bottom of the casing. The arm b'' is pivoted within the casing and is prefer-

ably so formed that when free to move on its pivot its end adjacent the tumbler b'' will fall to the bottom of the casing. To assist this gravity operation of the arm b'', it is provided with an enlarged portion b'', which acts as a counterweight and also as an operating-surface for the arm. When the end of the arm adjacent the tumbler is at the bottom of the casing, the portion b'' moves out to a position as shown in Fig. 2. The tumbler b'' is provided with a projection b''', which is adapted to engage with a serrated portion b'' of the casing. Should an attempt be made to move the bolt or latch b' through the knob and spindle, the bolt or latch will engage the tumbler and force the projection b''' into one of the serrations. This engagement of the serration by the tumbler will hold the bolt or latch should the end of the arm b'' fall while the attempted movement of the bolt or latch is continued through the knob or spindle.

In the application of my invention to a door controlling an entrance to an elevator well or hatchway at a landing I provide means for holding the arm b'' raised to have the tumbler b'' behind the bolt or latch, and thus prevent the door being opened except when the elevator-car is in proper position at the landing. These means are operated by the elevator-car when the elevator-car is in proper position at the landing. As shown, the means for holding the end of the arm b'' raised consists of a lever D, so arranged or counterweighted as to have its end d push in the portion b'' of the arm b'' to move the arm b'' on its pivot and have its end move the tumbler b'' behind the bolt or latch. The other end, d', of the lever may be provided with a roller and is adapted to be engaged by a cam or projection E, so arranged on the elevator-car that it will move the lever D on its pivot to allow the end of the arm b'' to fall only when the elevator-car is in proper position at the landing. The lever may be pivoted to some fixed part of the well or pit and adjacent the lock B.

The operation of the lock in connection with an elevator-car is as follows: Normally

- the lever D operates the arm b^6 to have it move the tumbler behind the bolt or latch, in which position of the tumbler (see Fig. 1) the bolt or latch cannot be withdrawn from its keeper.
- 5 When an elevator-car is at the landing and in proper position, the cam E will rock the lever D on its pivot to move its end d from out of engagement with the arm b^6 and allow the end of the lever and the tumbler to fall to the position shown in Fig. 2, in which position of the tumbler the bolt or latch can be moved out of its keeper and the door opened. If, however, any one is trying to unlatch the door by attempting to turn the spindle-sleeve b^4 as 10 the car passes a landing, the tumbler b^5 will be held behind the bolt or latch b^1 by the pressure on the spindle-sleeve, so that the door will remain locked.
- What we claim as our invention is—
- 20 1. The combination in a door-lock, of a casting, a bolt or latch, means for moving the bolt or latch into and out of its keeper, a tumbler to prevent the bolt or latch being moved out of its keeper, means for projecting the 25 tumbler behind the bolt or latch, and means for preventing a movement of the tumbler when the bolt or latch is pressed against said tumbler.
2. The combination in a door-lock, of a casting, a bolt or latch, means for moving the bolt or latch into and out of its keeper, a vertically-movable bolt or tumbler to prevent the bolt or latch being moved out of its keeper, means for lifting the tumbler into locking position, and means operated upon a movement 35 of the bolt or latch for retaining the tumbler in said locking position.
3. The combination in a door-lock, of a casting, a bolt or latch, means for moving the 40 bolt or latch into and out of its keeper, a tumbler to prevent the bolt or latch being moved out of its keeper, means for projecting the tumbler behind the bolt or latch, and means carried by the tumbler for engaging said casting to prevent a movement of the tumbler
- when the bolt or latch is pressed against said tumbler.
4. The combination in a door-lock, of a casting having a serrated portion, a bolt or latch, means for moving the bolt or latch into and out of its keeper, a tumbler adapted when moved behind the bolt or latch to prevent movement of the bolt or latch, means for moving the tumbler behind the bolt or latch and a projection carried by the tumbler which is 55 adapted for engagement of the serrated portion.
5. The combination in a door-lock, of a casting having a serrated portion, a bolt or latch, means for moving the bolt or latch into and 60 out of its keeper, a tumbler adapted when moved behind the bolt or latch to prevent movement of the bolt or latch, means for moving the tumbler behind the bolt or latch, and a projection carried by the tumbler which is 65 adapted for engagement with the serrated portion, which engagement prevents the tumbler from moving from behind the bolt or latch while the bolt or latch is pressed against the tumbler.
- 70 6. The combination of a door closing the entrance to an elevator well or hatchway, a lock for said door, said lock comprising a casting having a serrated portion, a bolt or latch and a tumbler carrying a projection; a pivoted arm for moving the tumbler behind the bolt or latch to prevent the bolt or latch being withdrawn from its keeper, and a device operated by the elevator-car for effecting said arm to permit the tumbler to move from behind the bolt or latch.
- 75 In testimony whereof we have signed our names to this specification in the presence of two subscribing witnesses.

NORTON P. OTIS.
AUGUST SUNDH.
